Primary Examiner — Susan Bennett Hattan*Assistant Examiner* — Barbara Blanton Lohr(74) *Attorney, Agent, or Firm* — Nixon & Vanderhye P.C.(57) **CLAIM**

The ornamental design for a “film sheet for use in antiballistic articles,” as shown and described.

DESCRIPTION

FIGS. 1 and 2 are top and bottom plan views, respectively, of a film sheet for use in antiballistic articles which embodies our new and original design therefore, the side views thereof being unornamented; and,

FIGS. 3 and 4 are top and bottom perspective views, respectively, of FIGS. 1 and 2.

The broken lines in the drawing represent the bounds of the claimed design and form no part of the claimed design.
